(57) **CLAIM**

The ornamental design for a multispace parking pay station, as shown and described.

DESCRIPTION

FIG. 1 is a top front perspective view of a multispace parking pay station, showing my new design;

FIG. 2 is a front elevational view thereof;

FIG. 3 is a top front perspective view thereof, shown in a used condition;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings represent portions of the multispace parking pay station that form no part of the claimed design.

All surfaces not shown form no part of the claimed design.

1 Claim, 7 Drawing Sheets(56)
